EDGE LABELING MECHANISM

Clifford E. Ives, Wilmette, Ill., assignor to United States Gypsum Company, Chicago, Ill., a corporation of Illinois

Application March 23, 1931, Serial No. 524,543

9 Claims. (Cl. 216—20)

This invention relates to an apparatus for the manufacture of gypsum or other board, and has reference more particularly to an apparatus of the class described, suitable for applying a pasted 5 label to the edge of moving strips of material, such as gypsum board.

In the manufacture of composition board, such as gypsum plaster and wall boards, it is customary to form the board by depositing a plastic 10 composition composed mainly of calcined gypsum and water, between the upper and lower cover sheets of the board to be formed, and then folding the edges of the paper cover sheet about the plastic material to completely enclose the latter 15 with paper. The board is allowed to set while it is moved continuously, is then cut into lengths and passed through a highly heated drying kiln which serves to completely dry the board ready for shipment. The temperature of the drying 20 kiln is usually so high that there is a tendency to recalcine the gypsum in the edges of the board, thus making the edges rather weak and having a poor bond with the paper.

I desire to apply a narrow label in the form 25 of a continuous strip to the edge of the composition board. This label carries sales indicia, such as trade marks, patent numbers, etc. It is important that the label be exactly positioned on the edge of the board so that it will not extend beyond either face of the board. It is also essential 30 that the strip be firmly attached to the board by suitable adhesive. While the boards are usually only $\frac{3}{8}$ " to $\frac{1}{2}$ " in thickness, I have found that the addition of the strip label serves materially 35 to retain the moisture in the edge of the board and prevent recalcination of the core material. In applying the strip label, it is desirable that a continuous supply of the label strip be maintained so that unlabeled board will not be 40 produced.

An object of this invention, therefore, is to provide an apparatus for applying a continuous strip of labeling material to the edge of composition boards which are manufactured in continuous 45 strips.

Another object of this invention is to provide an apparatus of the class described which will position the labeling strip accurately on the edge of the board and will also insure a continuous 50 supply of the strip material.

A further object of the invention is to provide a method of retaining moisture in the edges of the board while the board is passing through the drying kiln so as to prevent recalcination of the core 55 material in the board; also to improve the plaster boards and strip labeling apparatus in other respects hereinafter specified and claimed.

Reference is to be had to the accompanying drawings forming a part of this specification, in 60 which

Fig. 1 is a plan view of a plaster board machine with my improved edge labeling apparatus in place,

Fig. 2 is a side elevation of the apparatus shown in Fig. 1,

Fig. 3 is a sectional elevation through the apparatus taken on line 3—3 of Fig. 1,

Fig. 4 is a sectional elevation through the apparatus taken on the line 4—4 of Fig. 1,

Fig. 5 is a sectional view through the signaling apparatus taken on line 5—5 of Fig. 3,

Fig. 6 is a sectional elevation through the wetting pad taken on line 6—6 of Fig. 2,

Fig. 7 is a view similar to Fig. 4 but showing a modified form of apparatus for making a narrow width board, and

Fig. 8 is a fragmentary perspective view of a portion of a pressing shoe.

Plaster board or other composition board to which the edge label is to be applied, is usually composed mainly of a core 10 of gypsum or other suitable cementitious material, said core having an upper cover sheet 11 on its upper surface, and a lower cover sheet 12 on its lower surface. The lower cover sheet 12 is preferably provided with an upward fold 13 and an inwardly turned fold 14 on each edge, the fold 14 preferably underlying the outer edge of the cover sheet 11 and being adhesively attached thereto. The outer edge of the cover sheet 11 may be chamfered or provided with a feathered edge if desired to make a smooth face board. After introducing the plastic core material 10 between the cover sheets 11 and 12, the former plaster board strip is allowed to pass a considerable distance to give time for the plaster of Paris to set in solid form. During this setting period, the plaster board is carried by a belt 15 supported upon idler rollers, 16, the latter being mounted upon shafts 17 which are rotatably supported in bearings 18 on framework 19.

After the continuous strip of plaster board has set to solid form, and before it is cut into suitable lengths and passed through the dryer, the edge label 20 is applied to the edge of the plaster board on top of the fold 13. This edge label is usually $\frac{3}{8}$ " or $\frac{1}{2}$ " in width and is supplied in the form of a roll 21 of comparatively large diameter. The inside of the tape is gummed so that only wetting of the gummed surface of the tape is required before pressing it into contact with the fold 13. Roll 21 is preferably supported at its center on a hub 22 which has a restricted, threaded section 23, the latter passing through a sheet of insulating material 24, such as laminated, phenolic condensation products. The section 23 also passes through the center of a disc of insulating material 25 and is provided with a nut 26 screwed on the threaded section so as to secure the disc 25 to the disc 24. The discs 24 and

26 are mounted to rotate with the section 28, the rotation being caused by the tape 20 being continuously unwound from the roll 21, a friction contact existing between said roll 21 and disc 24. 5 A bolt 28 passes co-axially through the hub 22 and is provided with a threaded section 29 of reduced diameter, which passes through a disc of insulating material 30, being secured thereto by a nut 31. The outer edge of the disc 30 is 10 preferably secured by screws 32 to a metal plate 33, the parts being so proportioned that an appreciable clearance between the disc 24 and plate 33 is maintained at all times to avoid friction contact therebetween. The plate 33 is preferably 15 inclined at an angle to the horizontal as seen in Fig. 3, being supported by a bracket 35 connected to said plate by suitable bolts 36. The bracket 35 is secured to main longitudinal channels 37 of the board machine by means of bolts 38. The 20 plate 33 is preferably oblong in shape so that two of the discs 24 and rolls 21 may be mounted upon each plate. When one roll is exhausted, the second roll may be immediately connected in to supply the tape to the edge of the plaster board 25 while the first roll is being replaced.

After the tape or label strip 20 leaves the roll 21, it passes around the small idler pulley 40 which is rotatably supported upon the plate 33. The tape must now be wet on its gummed surface to render said surface sticky, and for this purpose I provide a wetting pad 41 of felt or other suitable fibrous material, said pad being retained in a rectangular shallow box 42, having a loose fitting cover 43. The box 42 is preferably in the form of an angle having the horizontal legs 44 thereof secured to the plate 33 by means of bolts 45. The lower wall of the box 42 has a cut out portion 47 which serves to permit the gummed surface of the tape to contact directly with the fibrous material 41 and also permits any excess water to drain away. The water for moistening the fibrous material 41 is supplied through a pipe 48 screwed into the bottom of plate 33, said pipe being connected to a liquid measuring device 49 of standard design, said device preferably being of the type commonly used as oilers for machinery.

This measuring device may consist of a glass cylinder 50 retained between caps 51, a central tube 52 having a lower orifice 53, passing downwardly through the upper cap 51. An adjusting head 54 connected to the upper end of the tube 52 outside the cap 51 is knurled to permit manual rotation of the tube 52 so as to regulate the amount of water flowing out of the orifice 53. A lever 55 is also associated with the upper end of the tube 52 for opening or completely shutting the orifice 53 if desired to stop the flow of water. A sight glass 57 is provided in the pipe 48 below the bottom cap 51 so that an observer can see the rate of flow or dropping of the water from the measuring device. A water supply pipe 60 is also connected to the bottom cap 51, being provided with a filter 62 carried by a suitable supporting bracket, and also being provided with a shut-off valve 63 and a drain cock 64. In this way a measured quantity of water is supplied to the fibrous pad 41 at a uniform rate of flow. It should be understood that my apparatus may be applied to both edges of the plaster board in which case a branch supply pipe 65 will also pass underneath the board machine to the opposite side, being connected to a liquid measuring device similar to that described.

55 After the gummed tape is moistened on its sur-

face, it passes inwardly toward the edge of the board and is firmly pressed thereon by means of a pressing shoe 66. This shoe 66 is provided with a plate 67 lying above the plaster board edge and is also provided with a U-shaped plate 68 connected by bolts 69 to a horizontally extending bar 68 so as to slidably support said shoe on said bar. Where the tape 20 first contacts with said shoe, the latter is provided with a rounded shoulder 66a, (Fig. 8) and flanges 66b on each 10 edge of said shoe which serve to define the path of the tape so as to accurately position the tape midway of the edge of the board. A washer 70 serves to confine a spring 72 between said washer and the plate 67a. The washer 70 bears against 15 a bracket 74 welded to the rod 69, said bracket being pivotally supported on a pivot bolt 76 secured to vertical standards 77 secured to the main channel 37 of the plaster board machine. A stop bolt 78 is secured to each standard 77 20 so as to engage the outer end of rod 69 and limit the counter-clockwise movement of said rod when the shoe 66 is lifted away from the edge of the board for cleaning, etc. After the tape 20 passes beyond the shoe 66 a brush 80 contacts with said 25 tape so as to aid in firmly and adhesively attaching the tape to the edge of the plaster board. A second shoe pressing device may be provided beyond the brush 80 is desired so as to further insure a firm application of the tape to the edge of the 30 plaster board.

After the tape has been applied to the plaster board edge, the plaster board passes forwardly to a cutting knife of standard design which is adapted to cut the same to desired lengths. 35 These lengths of plaster board then pass through a drying kiln having highly heated air moving at a high velocity to dry the moisture out of the plaster board. Owing to the temperature of the kiln, it has been previously found that the 40 gypsum core material in the edges of the board tends to recalcine, thus making the edges weak and destroying the bond between the paper and the core. However, I have found that when the tape is applied to the edge of the plaster board, 45 it serves to retain the moisture in the board core and prevent recalcination, producing boards of superior quality having attractive edges bearing the trade mark and other indicia which I desire to apply.

In order that the board machine operator may see from a distance when a roll is exhausted, I preferably provide a signalling device in the form of a standard electric lamp 81 which is in circuit 82 with a source of electric current. The ends 55 of the circuit 82 are connected to terminal posts 83 and 84 which are preferably of metal and are provided with wire connecting screws 85 in their outer ends. These terminal posts 83 and 84 are preferably hollow to receive annular brushes 86 60 which bear against contact segments 87 and 88 which are mounted on the insulation disc 25. The brushes 86 are resiliently urged into contact with the segments 87 and 88 by means of coil, compression springs 89 contained within the terminal posts 84. As seen in Fig. 5, the segment 87 is greater than 180 degrees and the segment 88 is less than 180 degrees, so that when the brushes are in the position shown in Fig. 5, the circuit is closed and the lamp 81 is lighted. Insulation 70 spacers 90 are interposed between the ends of the segments 87 and 88 so that when one of the brushes 86 contacts with the segment 88 and the other brush contacts with the segment 87, the circuit is broken and the lamp 81 goes out. It 75

will thus be seen that as the tape 28 is unwound and the disc rotates, the lamp 81 continues to flash intermittently, but when the roll 21 is completely unwound, the light is either off or burns continuously, depending upon the position of the carbon brushes 86, and thus signals the operator to connect in the other roll carried upon the plate 33. When the roll is large in diameter, the light flashes slowly, and vice versa.

10 When a narrow plaster board is to be manufactured, a spacer sleeve 92 (Fig. 7) is positioned on the rod 69 between the spring 72 and plate 67a so as to maintain substantially the same pressure of the shoe 66 against the label strip 28.

15 In operation the rolls or paper 21 are placed with their center co-axial with the hub 22 and with the face of the roll resting upon the rotary disc 24. The paper strip 28 unwinds and passes with its gummed surface in contact with the fibrous pad 41 which is supplied with water from the measuring device 49. The moistened paper then passes under the shoe 66 which is pressed inwardly by spring 72 to cause the moistened surface to press firmly against the edge of the plaster board. A brush 80 then aids in securing adhesion between the tape and the plaster board and a second shoe 66 presses against the tape to complete the adhesion thereof. As long as the roll is not exhausted and keeps rotating, the lamp 81 continues to flash intermittently due to the action of the brushes 86 on the contact segments 87 and 88. When the roll is exhausted, the lamp 81 either stays lit or goes out, indicating to the operator that the second roll of paper carried by the plate 33 should be applied to the edge of the plaster board.

If desired, ungummed strips of paper may be used and the adhesive liquid applied by means of the fibrous pad 41. The label may also be applied to the boards after drying, if desired. When the boards are stacked in face to face position, the label strips appear on the edges of the board and give the product an attractive appearance.

45 I would state in conclusion that while the illustrated example constitutes a practical embodiment of my invention, I do not wish to limit myself precisely to these details, since manifestly, the same may be considerably varied without departing from the spirit of the invention as defined in the appended claims.

Having thus described my invention, I claim as new and desire to secure by Letters Patent:

1. In apparatus for applying strip material to the edge of wallboard or the like, means for supporting a roll of strip material, means for rendering one face of said strip adhesive, and means for pressing said strip against said edge, including a non-rotating shoe member bearing against said edge, resilient means to constantly urge said shoe against said edge, and a rod-shaped element of substantial length slidably supporting said shoe, the length of said rod-shaped element permitting adjustment of said shoe to accommodate varying widths of material to which the edge strip is applied.

2. In apparatus of the class described, means for exerting a resilient pressure, comprising a rod-shaped member pivotally mounted adjacent one end, a pressing element slidably carried by said member, and resilient means for maintaining pressure on said pressing element in operation.

3. In apparatus of the class described, means

for exerting a resilient pressure against the edge of an object, comprising a rod-shaped member, a pressing element slidably carried by said member, means on said pressing element adapted to lie upon said object and define the relation of the pressing element to said edge, and resilient means for maintaining pressure of the pressing element against said edge.

4. Means for pressing a strip of material against the edge of a flat, moving object, comprising a rod-shaped member, a pressure shoe slidably carried by said member, means on said shoe for guiding said strip into position, means on said shoe adapted to lie upon said object and define the relation of the shoe to said edge, and resilient means for maintaining pressure of the shoe against said edge.

5. A pressure shoe of the class described, comprising means for slidable association with a support member, a smooth pressure edge, means overhanging said edge and adapted to rest upon the object operated upon to define the relation of said edge to the edge of the object, and an integral guide formed adjacent said shoe edge for guiding strip material to pass between said shoe edge and the edge of said object.

6. In apparatus of the class described, means for supplying strip material, and means for pressing said strip against an object, comprising a pressing element slidably carried by a rod-shaped member of substantial length, and resilient means for urging said pressing element against said object, the length of said rod-shaped element being such as to permit operation upon material of varying dimensions by slidable adjustment of said pressing element.

7. In apparatus of the class described, means for supporting a moving sheet of wallboard or the like, means for supplying a strip of material for application to the edge of said sheet, and means for pressing said strip against said edge comprising a rod-shaped member mounted for vertical pivotal movement on said supporting means, a pressing element slidably carried by said rod-shaped element, and means for maintaining said pressing element in pressure relation to said edge.

8. In apparatus of the class described, means for supporting a moving sheet of wallboard or the like, means for supplying a strip of material for application to the edge of said sheet, means for pressing said strip against said edge comprising a rod-shaped member mounted for vertical pivotal movement on said supporting means, a pressing element slidably carried by said rod-shaped element, means for maintaining said pressing element in pressure relation to said edge, and means for limiting the pivotal movement of said rod-shaped member.

9. In combination with a board forming machine, means for applying a strip of material to the edge of a moving board sheet, said means comprising a plate member secured to the edge of the board carrier and extending slantingly upwardly and inwardly of said carrier, means on said plate for rotatably receiving a roll of said strip material, and means for applying said strip to said board edge, the angle of said plate member relative to said board sheet being such as to permit free movement of said sheet thereunder as well as to permit ready accessibility for changing rolls or the like.

CLIFFORD E. IVES.
